LATHER-PRODUCING DEVICE

Filed Feb. 19, 1948

UNITED STATES PATENT OFFICE

2,532,565

LATHER-PRODUCING DEVICE

Ralph Miller, Muncie, Ind.

Application February 19, 1948, Serial No. 9,352

5 Claims. (Cl. 259—4)

1

The present invention relates to lather-producing devices, and more particularly to an instrumentality comprising the combination of a receptacle from which a water solution of soap or the like is supplied to a current of air to be mixed therewith and converted into a lather of any desired consistency which is ejected from a nozzle.

The device has been invented particularly for use in connection with ordinary household vacuum cleaners; for the purpose of providing a copious supply of heavy lather which will be useful in shampooing rugs, carpets, upholstery and the like, and it has been used successively for that purpose. However, it is useful also in other relationships and for other purposes, wherever the production of a controlled supply of light or heavy lather or soap suds is required.

Principal objects of the invention are to provide a device of the character indicated which will be simple and durable in construction, fool-proof and reliable in use, and unfailingly efficient in performing its intended functions.

Other objects are concerned with providing a device of the character indicated in a form which is highly versatile, so that it can be used for numerous purposes where a supply of lather or soap suds is required.

Another object is to make the device of parts that are readily separated to permit the internal passageways to be cleaned and easily reassembled after each period of use.

Other objects and advantages will be apparent from the following description of an embodiment which is illustrated in the accompanying drawing and which has been tried and tested in actual use and found entirely satisfactory and which is accordingly at present preferred.

In the accompanying drawing;

Figure 1 is a side elevational view of a complete embodiment of the invention, with certain portions of the device shown in section;

Fig. 2 is a front elevational view of the mixing unit;

Fig. 3 is a perspective view of the nozzle;

Fig. 4 is an exploded perspective view of the nozzle; and

Fig. 5 is an axial sectional view of the terminal end portion of the nozzle.

Generally speaking, the invention includes the combination of a barrel through which a current of air is blown and into which a small jet of a water solution of soap or the like is introduced and carried by the air stream through a unit providing a multiplicity of small passage-

2

ways in which the liquid jet is thoroughly dispersed in the air so that the air and liquid are intimately intermingled to produce a mass of lather or soap suds which issues from a nozzle provided at an end of the barrel.

Referring to the drawing, A designates a barrel member of generally tubular shape conveniently made of sheet or extruded metal formed with an inside diameter of the order of about one and one-quarter inch. While such material, form and proportions are preferred, none of them is critical, so that it is possible to make the barrel otherwise.

One end of the barrel, shown at the right hand side of Fig. 1, is provided with a fitting designated 4, for connecting with a tube or hose by which a stream of air may be supplied to the barrel, and the other end of the barrel is provided with a sleeve 2 which serves as a nozzle. The inlet fitting 4 may be, as shown in the drawing, simply the terminal end of a vacuum cleaner hose attachment for supplying a stream of air, or it may be a conventional type of nipple or connector for attaching any other air-supply conduit.

The nozzle 2 is best made in the form of a sleeve of metal like that of the barrel A but of large enough diameter, and preferably provided with a lengthwise expansion slot 3, to make a resilient friction fit telescopically over the barrel so that it can be easily removed and replaced.

Soldered or otherwise secured to what may be regarded as the bottom of the barrel member A is the cap 4 of a reservoir jar 5 onto which the cap is threaded or otherwise removably attached. The cap is closed throughout its top in the usual manner but is more or less centrally perforated to mount and pass a small diameter tube 6 which extends from a point near the bottom of the jar 5 up through an opening in the barrel member A to about the axis of the barrel, where the tube is bent forwardly substantially along the axis to an open terminal end. The portion of the tube adjacent to this end is mounted on an arm or bracket 7 in a funnel 8 which is formed by spinning or otherwise tapering the forward end of the barrel member A. An opening 9 is formed in the taper, around the end of the tube 6, so that air passing through the barrel member will be constricted by the funnel 8 to move at increased velocity through the opening 9 and thereby aspirate through the tube 6 whatever liquid may be contained in the jar 5, as shown at 10.

In actual practice for the principally intended

purposes of the invention, this liquid may be a water solution of soap.

The terminal end of the nozzle 2 encloses an assembly of screen wire mesh elements through which the current of air carries the jet of liquid from the end of the tube 6 so that it is thoroughly broken up in passing through the screen interstices and mingled intimately with the air to produce a body of lather.

A convenient mode of mounting the discs of screen wire mesh consists in inwardly flanging the nozzle, as shown at 11, and forming a unit of telescoping sleeves 12 and 13 to serve as a casing for a plurality of screen wire mesh discs 14, which are held in more or less compact, engaged relation depending on the setting of the sleeves 12 and 13. The unit provided by these sleeves fits more or less snugly in the nozzle 2, up against the flange 11. Its distance from the end of the liquid jet tube 6 may be adjusted by moving the nozzle 2 more or less along the barrel member A, thus altering the properties of the lather which is formed by impinging the jet on the plurality of discs and passing the liquid through them with the current of air.

It will be recognized that the barrel A at no time carries anything but air, so that it never requires cleaning. The liquid soap solution readily drains out of the tube 6 after each period of using the device. Only the nozzle 2 has any contact with lather, and this nozzle is easily cleaned by disengaging it from the barrel and flushing it and the wire mesh disc assembly out with a stream of clear water, as by holding it for a moment under a kitchen sink faucet.

Numerous changes in the specifically disclosed embodiment may be made without departing from the essential principles of the invention. Those principles are pointed out by the appended claims.

I claim:

1. A lather-producing device comprising a barrel having at one end an inlet for a current of air, means for supplying air under pressure to said inlet, a plurality of wire mesh discs filling the barrel adjacent to its other end, and a tube having an outlet in an intermediate part of the barrel for conducting a water solution of soap into the current of air so that a jet of said solution will be blown through the plurality of discs and be aerated thereby to produce a lather, the side walls of the barrel being imperforate between the outlet of the tube and the wire mesh discs.

2. A lather-producing device comprising a barrel having at one end an inlet for a current of air, means for supplying air under pressure to said inlet, a plurality of wire mesh discs filling the barrel adjacent to its other end, and a tube having a portion extending lengthwise through an intermediate part of the barrel for conducting a water solution of soap to an outlet in the current of air so that a jet of said solution will be blown through the plurality of discs and be

aerated thereby to produce a lather, the side walls of the barrel being imperforate between the outlet of the tube and the wire mesh discs.

3. A lather-producing device comprising a barrel having at one end an inlet for a current of air, means for supplying air under pressure to said inlet, an assembly comprising a plurality of wire mesh discs arranged in contact with each other adjacent to the other end of the barrel, and a tube having an outlet in an intermediate part of the barrel for conducting a water solution of soap into the current of air so that a jet of said solution will be blown through the assembly and be aerated thereby to produce a lather, the side walls of the barrel being imperforate between the outlet of the tube and the wire mesh discs.

10 4. A lather-producing device comprising a barrel having at one end an inlet for a current of air, means for supplying air under pressure to said inlet, an assembly comprising a plurality of wire mesh discs arranged in contact with each other adjacent to the other end of the barrel, and a tube having an outlet in an intermediate part of the barrel for conducting a water solution of soap into the current of air so that a jet of said solution will be blown through the assembly and be aerated thereby to produce a lather, the side walls of the barrel being imperforate between the outlet of the tube and the wire mesh discs.

15 5. A lather-producing device comprising a barrel having at one end an inlet for a current of air, means for supplying air under pressure to said inlet, an assembly comprising a plurality of wire mesh discs arranged in contact with each other adjacent to the other end of the barrel, and a tube having an outlet in an intermediate part of the barrel for conducting a water solution of soap into the current of air so that a jet of said solution will be blown through the assembly and be aerated thereby to produce a lather, the side walls of the barrel being imperforate between the outlet of the tube and the wire mesh discs.

20 6. A lather-producing device comprising a barrel having at one end an inlet for a current of air, means for supplying air under pressure to said inlet, an assembly comprising a plurality of wire mesh discs arranged in contact with each other adjacent to the other end of the barrel, and a tube having an outlet in an intermediate part of the barrel for conducting a water solution of soap into the current of air so that a jet of said solution will be blown through the assembly and be aerated thereby to produce a lather, the side walls of the barrel being imperforate between the outlet of the tube and the wire mesh discs.

25 7. A lather-producing device comprising a barrel having at one end an inlet for a current of air, means for supplying air under pressure to said inlet, an assembly comprising a plurality of wire mesh discs arranged in contact with each other adjacent to the other end of the barrel, and a tube having an outlet in an intermediate part of the barrel for conducting a water solution of soap into the current of air so that a jet of said solution will be blown through the assembly and be aerated thereby to produce a lather, the side walls of the barrel being imperforate between the outlet of the tube and the wire mesh discs.

30 8. A vacuum cleaner attachment for producing a lather for shampooing rugs and the like comprising a barrel, means for connecting one end of the barrel to a vacuum cleaner so as to

35 be supplied with a current of air under pressure therefrom, a reservoir attached to the barrel, means for causing a current of air in the barrel to aspirate a jet of a water solution of soap from the reservoir to an outlet in the intermediate portion of the barrel, and a plurality of wire mesh discs mounted in the barrel adjacent to its other end through which the current of air under pressure and the jet of solution will pass to be intimately intermixed so as to produce a lather, the

40 9. A vacuum cleaner attachment for producing a lather for shampooing rugs and the like comprising a barrel, means for connecting one end of the barrel to a vacuum cleaner so as to

45 be supplied with a current of air under pressure therefrom, a reservoir attached to the barrel, means for causing a current of air in the barrel to aspirate a jet of a water solution of soap from the reservoir to an outlet in the intermediate portion of the barrel, and a plurality of wire mesh discs mounted in the barrel adjacent to its other end through which the current of air under pressure and the jet of solution will pass to be intimately intermixed so as to produce a lather, the
